E. P. WAGGONER.
STEAM HEATER.

No. 402,635.

Patented May 7, 1889.

UNITED STATES PATENT OFFICE.

EDWARD P. WAGGONER, OF SYRACUSE, NEW YORK.

STEAM-HEATER.

SPECIFICATION forming part of Letters Patent No. 402,635, dated May 7, 1889.

Application filed August 10, 1888. Serial No. 282,402. (No model.)

To all whom it may concern:

Be it known that I, EDWARD P. WAGGONER, of Syracuse, in the county of Onondaga, in the State of New York, have invented new and useful Improvements in Steam-Heaters, of which the following, taken in connection with the accompanying drawings, is a full, clear, and exact description.

This invention relates to an improvement in "steam-heaters;" and it consists in certain novel peculiarities of the construction and arrangement of the same, substantially as will be hereinafter more fully set forth, and specifically pointed out in the claims.

15 In order to enable others skilled in the art to which my invention pertains to make and use the same, I will now proceed to describe its construction and use, referring to the accompanying drawings, in which—

20 Figure 1 is a side elevation of my improved heater; Fig. 2, a front elevation of the same; Fig. 3, a longitudinal vertical section of the device, taken on the line $x-x'$ of Fig. 4; and Fig. 4 is a horizontal section taken on a line 25 as indicated by $y-y'$ in Fig. 3.

I prefer to construct my heater of a substantially square or rectangular form in general outline, as clearly shown in the drawings, the peculiar form and construction 30 shown giving me a largely-increased heating-surface in proportion to the amount of grate-surface necessary; and the form of my sections, it will be noted, is such as to spread the water in the boiler into thin sheets, more effectively acted upon by the heat generated in the fire-pot.

Each side or section of my heater is cast or formed hollow and separate from each other section, as clearly seen in Figs. 3 and 40. The lower part of each side section is thus formed into a thin hollow box, a , surrounding the fire-pot and forming the walls of the same; and in the lower walls of each section is also formed an opening or openings, a' , these openings in the several sections being arranged to coincide when the sections are bolted together and form feed-passages, so that when the heater is put together the different sections communicate and form 45 practically one hollow shell around the whole heater. The upper part of each side section is formed with a series of hollow projections,

a^2 , opening, of course, into the main water-chamber and projecting out over the fire-pot, so that the heat and products of combustion 55 are compelled to pass up through the spaces or flues between these hollow projections, and thus act on the largely-increased surface, while these hollow projections, being narrow, spread the water contained therein out in thin 60 sheets in a manner to give the very best results and extract the utmost heat from the fuel. Each section is also formed with one, two, or more smoke-flues, b , which pass vertically through the hollow section and open 65 freely through its top and through its lower outer side wall, as fully seen in Fig. 3.

Upon the top of the heater, the sides or main body of which is so formed, is secured a flat hollow top section or steam-dome, c , a space, 70 b' , being left between the dome and boiler proper to permit the smoke and products of combustion to pass freely over the side sections and down through the flues b , and a steam-connection, c' , is formed between the 75 top section or dome, c , and each of the side sections, so that free circulation is had at all times throughout the parts of the heater.

Upon the top face of the heater-sections and outside of the opening of the smoke-flues 80 I form the raised projection or chamber a^4 , which is extended up to meet the top section of the heater. When the heater-sections are in position, the ends of these projecting chambers abut and aid in inclosing the space b' 85 and preventing the passage of smoke, &c., over the top of the heater-sections, causing the same to pass down the flues.

Through such of the sections a as are necessary I form passages to connect with the 90 usual and necessary fire-door, d , &c., and provide also an ash-pit door, d' , and the other usual and necessary appurtenances of this nature.

In the bottom of the fire-pot I place the 95 grate, consisting in this case of a series of rocking bars, d^2 , secured in a square or rectangular frame, e , which is supported upon flanges e' on the sides of the ash-pit, and thus when any repairs are needed I open a door, e^2 , 100 provided for that purpose, and simply draw out the whole grate-frame, readily sliding it back upon its supporting-flanges when completed, and by this construction considerable

time and expense are saved in making repairs, it not being necessary to take apart the heater, as is so often the case.

The heater is surrounded by an outer shell, 5 f , of any suitable material, provided with a smoke-escape pipe, f' , and in Fig. 3 I have shown in dotted lines a deflector, f^2 , by which the products of combustion, as they leave the flues b , are made to circulate around the out- 10 side of the hollow fire-pot sections a before they can reach the smoke-escape pipe, thus utilizing these products to the last degree.

For convenience of operation I provide a magazine, g , suspended over the fire-pot and 15 having a hood, g' , with door g^2 on top of the shell to admit the fuel. It will be noted that I provide a pipe, h , connecting the hood with the smoke-escape pipe f'' , and in this connection I place a valve, h' , normally closed. This 20 valve is provided on the outside of the connection h with a lever-arm, h^2 , one end of which is provided with a weight, m , and the other with a small rod, m' , extended alongside of the hood in a suitable guide and adapted to 25 contact with the magazine-door or a projection on the same, as in Fig. 1. When the magazine-door is opened, the weight at once opens the valve in the connection h , and any gas that may rise through the magazine is 30 carried off to the chimney and not allowed to escape into the room. When the door is closed again, it engages and pushes back the rod m' and automatically closes this valve till again used.

35 The various sections of the heater are firmly secured together by small bolts n , which are passed through one hollow section and screwed into a cross-bar, n' , in the adjoining one, so that there are no long through-bolts exposed 40 to the action of the heat. Proper packing is of course used at the points where water and steam connections are made from section to section, and the joints are thus made tight and no leakage occurs.

45 It will be obvious that the peculiar form of side section with the thin hollow projections gives me a greatly-increased surface, and that the passage of the products of combustion through and around these projections, then 50 down through the flues and around the fire-pot before escaping, utilizes the last degree of heat produced by the fuel and renders the heater economical. The construction, too, in flat hollow sections renders fewer patterns 55 necessary and saves materially in the first cost of the heater.

Having thus fully described my invention, what I claim as new, and desire to secure by Letters Patent, is—

60 1. The herein-described heater, having each side thereof formed of a separate section connected together and formed on their inner faces with integral heating-chambers projecting over the fire, substantially as and for the 65 purpose specified.

2. In an angular steam-heater, a hollow section forming one side of said heater, flues

running through said section, openings adapted to be connected to the other sections, and projecting hollow chambers formed integral 70 with the heater-section and extending over the fire, substantially as and for the purpose set forth.

3. In a steam-heater, the section composed of the lower box, a , and a series of projections above the box on the inner face of said heater-section and extending over the fire, and a bearing-face on said heater provided with a water-passage, substantially as and for the purpose set forth. 80

4. In a steam-heater, the section composed of the lower box, a , a series of hollow projections above the box a and extending over the fire, and the raised chamber a^4 on the top face of the heater, substantially as and for 85 the purpose set forth.

5. In a steam-heater, the heater-section composed of the lower box, a , a series of integral projecting hollow chambers above the box, the raised projecting chamber on the top 90 face of the heater-section, and the flues running through the heater and opening through the same on the inside of the said projecting chamber, substantially as and for the purpose set forth. 95

6. In a steam-heater, the heater-section composed of the lower box, a , a series of integral projecting chambers above the box, the raised projecting chamber on the top face of the heater-section, and the flues b , running 100 through the heater and opening on the inside of the projection a^4 and on the outside wall of the heater, substantially as and for the purpose set forth.

7. In a steam-heater, a main body formed 105 of flat hollow water-sections cast independently, each section being formed on the surface adjacent to the fire with a series of parallel hollow projections above the fire-box, and also with the vertical smoke-flue opening 110 through the top of the section and also through its lower side wall, substantially as and for the purpose set forth.

8. A steam-heater having each wall composed of a separate section or water-chamber 115 connected to the adjacent section, and its top composed of a horizontal section connected to the sections forming the heater-walls, substantially as and for the purpose set forth.

9. In a steam-heater the sides of which 120 meet each other at an angle, the combination of separate heater-sections composing the main body and provided with integral projecting heating-chambers, water-passages between the said sections, and flues extending downwardly from the top of the main body, with a top section imposed above the main body and a space inclosed by the top section, and the sections forming the walls of the heater, and water-passages between said top section and main body, substantially as 130 and for the purpose set forth.

10. In a steam-heater, the combination of the separate sections or water-chambers hav-

ing integral projecting heating-chambers and the raised projections on the top face thereof, connections between the heater-sections, with the top section abutting against the said 5 raised projection, connections between the heater-sections and top section, a space inclosed by said top section and heater-sections, and flues leading therefrom, substantially as and for the purpose set forth.

In testimony whereof I have hereunto signed to my name, in the presence of two attesting witnesses, at Syracuse, in the county of Onondaga, in the State of New York, this 21st day of May, 1888.

EDWARD P. WAGGONER.
